US00D585730S

(12) **United States Design Patent**
Fernandez

(10) **Patent No.:** **US D585,730 S**
(45) **Date of Patent:** **** Feb. 3, 2009**

(54) **MOUNTING SCREW WITH SELF-DRILLING
FEATURE**

(75) Inventor: **Julio A. Fernandez**, Doonnelon, FL
(US)

(73) Assignee: **Clairson, Inc.**, Newark, DE (US)

(**) Term: **14 Years**

(21) Appl. No.: **29/298,392**

(22) Filed: **Dec. 4, 2007**

(51) LOC (9) Cl. **08-08**

(52) U.S. Cl. **D8/387**

(58) Field of Classification Search **D8/387;**
411/387.1, 387.8, 387.3, 144, 378, 380, 403,
411/429

See application file for complete search history.

(57) **CLAIM**

The ornamental design for a mounting screw with self-drilling feature, as shown and described.

DESCRIPTION

FIG. 1 is a front perspective view of a mounting screw with self-drilling feature, showing my design;

FIG. 2 is a back perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof; and,

FIG. 8 is a right side view thereof.

The details shown in broken lines are for illustrative purposes only and form no part of the claimed design.

1 Claim, 7 Drawing Sheets
